UNITED STATES PATENT OFFICE.

HARRY W. HARDINGE, OF NEW YORK, N. Y.

TUBE-MILL.

No. 909,292.

Specification of Letters Patent.

Patented Jan. 12, 1909.

Application filed May 9, 1906. Serial No. 315,856.

To all whom it may concern:

Be it known that I, HARRY W. HARDINGE, a citizen of the United States, residing at New York, in the county and State of New York, have invented certain new and useful Improvements in Tube-Mills, of which the following is a specification.

My invention relates to grinding machines, more particularly the type in which the material to be ground or pulverized is tumbled in a rotating cylindrical drum, or "tubemill", as it is commonly known, with or without the aid of metal balls or other hard and non-friable bodies. The tubemill or drum is supported by and rotated on axially extending tubular trunnions, and in the usual form of apparatus the material is continuously introduced into the drum through one of the hollow trunnions by the agency of a screw conveyer working therein, or by gravity from a stationary hopper or other receptacle which discharges into the trunnion. These feeding devices possess certain defects, the most serious of which is the wear, between the rotating trunnion and the parts of the rotating parts or stationary part coöperating therewith, caused by the sand or grit which inevitably penetrates between such parts. Efforts have been made to reduce the wear by employing glands or stuffing boxes at the joints, but these expedients have proved at best only partially successful, and the necessity of frequent repairs has been but little bettered.

My present invention is directed to the improvement of the feeding devices, and has for its chief object to eliminate all parts between which and the tubemill there is relative movement, thereby eliminating the drawback above mentioned, and to provide feeding apparatus of the simplest character, but which will at the same time feed the material into the tubemill while the same is revolving.

To these and other ends the invention consists in the novel features of construction, arrangements of parts, and combinations of elements hereinafter described, and more particularly set forth in the claims.

A convenient embodiment of the invention is illustrated in the annexed drawing, in which—

Figure 1 is a side elevation of the inlet end of a tube mill, showing, in section, my improved feeding device applied thereto. Fig. 2 is an enlarged cross section of the feeding

device or scoop, on line *a—a*. Fig. 3 is a longitudinal section of a modified form of scoop.

The drum or tubemill is indicated by 1, and 2 designates one of the trunnions on which it revolves. This trunnion is tubular, as shown, and through it the material to be ground is introduced into the tubemill.

3 is a scoop, formed by a curved wall 4 and parallel side walls 5, 6. The curved wall is substantially spiral in form, and extends around a tubular member 7, thus forming around said member a spiral passage, opening into the same through an aperture 8. The tubular member projects outward from the wall 6 and is provided at its end with an outwardly extending radial flange 9, by which it may be bolted to a corresponding flange 10 on the trunnion 2, as clearly shown in Fig. 1. The scoop dips into a receptacle 11, into which latter a chute 12 discharges, delivering the material to be ground.

The operation of the device is as follows: As the tubemill revolves, in the direction of the arrow, the scoop dips into the receptacle and scoops up a quantity of the material. As the scoop continues to revolve, the load of material is carried, on the well known principle of the screw of Archimedes, up to the tubular member 7 and is finally discharged into the latter through the aperture 8, whence it passes through the hollow trunnion into the tubemill. This operation is repeated at every revolution of the tubemill, as will be readily understood.

It will be noted that as illustrated in Figs. 1 and 2, the tubemill, with the scoop arranged at that end, must rotate counter-clockwise.

In Fig. 3 is shown a scoop which may be reversed, so as to be used, if desired, with a clockwise or counter-clockwise rotation at will. In this form the tubular member 7 is open at each end, through the walls 5, 6, but has its extension 7^a removably secured by means of a flange 7^b, by means of which it may be bolted at either end of the tubular member. The open end of the latter is then closed by a plate 13. Assembled as in Fig. 3 the scoop can be reversed and secured to the trunnion 2 by means of the flange 9, whereupon the rotation of the tubemill can be reversed and the feed go on as before.

When the tubemill is to rotate counter-clockwise, as in Fig. 1, the extension 7^a and

plate 13 are simply exchanged and the scoop reversed, as will be readily understood.

From the foregoing it will be seen that the scoop is rigidly connected with the drum and its trunnion, and that there is therefore no relative movement between any of these parts. The trunnion simply rotates in its bearing, which can easily be protected. At the same time the feed of material, though in a sense intermittent, may be made sufficient for the capacity of the machine by making the scoop of proper size.

The specific form herein described is of course merely one embodiment of the invention, which may be embodied in a variety of forms without departure from its proper scope. Another species of the generic invention is described and claimed in my co-pending application filed of even date here-
20 with.

What I claim is:

1. The combination with a rotating tube-
mill having a tubular trunnion opening into

the same for the discharge of material there-
into, of a spiral scoop in detachable connec- 25
tion with the trunnion, having in the side
wall adjacent to said trunnion an aperture
in register therewith and having a similar
aperture in the opposite side wall, and a re-
movable closure over the last-mentioned ap- 30
erture, as set forth.

2. The combination with a rotating tube-
mill having a tubular trunnion opening into
the same, of a tubular member secured on
the end of the trunnion and in line therewith, 35
a spiral scoop removably secured to the tubu-
lar member, having an aperture in its con-
tiguous side wall in register with the interior
of the tubular member and having a similar
aperture in the opposite side wall, and a clo- 40
sure removably secured over the last-men-
tioned aperture, as set forth.

HARRY W. HARDINGE.
